UNITED STATES PATENT OFFICE.

AUGUSTUS RENTZ STEVENS, OF TAMPA, FLORIDA, ASSIGNOR OF ONE-HALF TO
J. S. LONG.

BOX-PRESS.

1,095,940.

Specification of Letters Patent.

Patented May 5, 1914.

Application filed August 19, 1913. Serial No. 785,547.

To all whom it may concern:

Be it known that I, AUGUSTUS R. STEVENS, a citizen of the United States, and a resident of Tampa, in the county of Hillsboro 5 and State of Florida, have made certain new and useful Improvements in Box-Presses, of which the following is a specification.

My present invention relates to box presses utilized to press and hold the cover on a 10 fruit box and the like during the time it is being nailed and strapped, and the object of my invention is to provide a simple and inexpensive apparatus which will be durable and effective in use and which embodies certain 15 novel features of construction, arrangement and operation to be hereinafter particularly referred to and pointed out in the claims.

In the accompanying drawings which 20 illustrate my invention, Figure 1 is a perspective view of my improved box press illustrating its practical application. Fig. 2 is a plan view. Fig. 3 is a side elevation. Fig. 4 is a central vertical transverse section 25 looking therethrough. Fig. 5 is a front elevation. Fig. 6 is a detail transverse section taken through one of the vertically movable oscillatory shafts and its tubular guide substantially on line 6-6 of Fig. 5. Fig. 7 is 30 a detail vertical section through the same parts. Fig. 8 is a detail perspective view of one of the bracket connections of the tubular supporting guides.

Referring now to these figures, my improved box press consists of a substantially 35 rectangular frame A upon the upper forward portion of which is supported the box receiving table B, the rear side uprights A' of the frame being extended above the surface 40 of the table B and at the rear thereof, and having brackets c secured thereto and to which are rigidly connected upright tubular supporting guides C these tubular supporting guides being provided with vertically 45 extending slots c' intermediate their ends, and the upper portion c² of which slots are gradually curved inwardly for substantially a quarter turn.

Mounted in the forward portion of the 50 frame A are a pair of upright parallel beams A² in the space between which works a foot lever D having a foot piece d at its forward end and having its rear end hinged at d' between rearwardly projecting parallel 55 brackets D' secured to and extending

rearwardly from the frame. Thus, the foot lever D is adapted for vertical swinging movement between the beams A² and upon its pivot d' and this beam may be locked in any desired adjustment by the means to be now described. Depending between the beams A² and hingedly connected at its upper end to the said beams, is a brake bar E, the lower free end of which extends downwardly through a conformable transverse slot in the foot lever D, and in engagement with the rear edge of which is an adjustable fixed set screw d² threaded through an upwardly portion of the foot piece d. Mounted on this foot piece forwardly of the bar E is a pivoted trip d³ through the rear end of which is threaded a set screw d⁴ adapted for engagement with the forward edge of the brake bar E and arranged in a plane above that of the engaging set screw d², as may be clearly seen by reference to Fig. 4.

A U-shaped connecting member F has a swiveled connection at its lower end to the foot lever D at a point intermediate the ends of the latter and has a similar connection at its upper end to an eye bolt g intermediate the ends of a horizontal equalizing bar G this bar extending longitudinally within the frame A at a point immediately in front of the rear uprights A'. Each end of the equalizing bar G is provided with an inverted U-strap g' through which a bolt h at the lower end of the respective presser shaft H is connected, thus providing for a swiveled connection of the presser shaft and at the same time providing for equal transmission of movement from the foot lever D to the presser shafts at opposite ends of the bar.

Each of the presser shafts H extends upwardly through one of the tubular supporting guides C and is provided at its upper end above the supporting guide with an adjustable angular arm h' in the outer end of which is adjustably secured the respective presser arm I, this arm being in the form of a substantially flat blade, as best shown in Figs. 1 and 2 in order to effectually press and hold a box top in place.

At a point intermediate its ends, each of the shafts H is provided with a guide pin h² extending into the guide slot c' of its respective supporting guide so that upon vertical movement of the presser shaft to re-

95

100

105

110

lease the box, the guide pins working into the upper curved end c^2 of the guide slots will cause rotative movement of the shafts through a quarter turn in order to swing the

5 presser blades I inwardly and rearwardly to longitudinal coextensive positions, it being noted that in these positions, as shown in Fig. 3, the presser blades will be entirely removed from the box and the latter thus

10 freed for more ready removal.

Extending between the upper ends of the rear frame uprights A', is a horizontal connecting beam J from an intermediate point of which depends an eye bolt j, which

15 serves as a support for the upper end of a retractile coil spring K, the lower end of which is connected to a bracket intermediate the ends of the equalizing bar G. Thus it

20 will be noted that the normal position of the presser blades I will be as shown in Fig. 3, although this may of course be controlled, where desired, by means of the stop mechanism including the set screws d^2 and d^4 in engagement with the brake bar E.

25 With the parts in their normal position, a box, for instance a fruit box and the like, such as indicated at L in Fig. 1, is placed on the table B with its open end uppermost and its top L' is placed thereon. The foot

30 lever D is then pressed down by the operator, who, at the same time, rocks the trip d^3 to release its set screw d^4 from the brake bar E. During lowering movement of the

35 presser shafts H, they are given a quarter turn in order to bring the presser blades I to transverse forwardly projecting positions, as clearly shown in Figs. 1 and 2 and in these positions they are lowered into engagement with the box top in order to press

40 and hold the same downwardly and in proper position, while it is being nailed and strapped. During this operation, the operator may continue to hold the foot lever D in lowered position, but it is preferable, and

45 almost universal in practice that the foot lever be released, allowing the trip d^3 to rock by gravity until its set screw d^4 engages the brake bar E and coöperates with the set screw d^2 to effect a frictional lock and hold

50 the foot lever in position. When the box lid

has been nailed and strapped in place, it is apparent that the parts will be returned to normal position, when the stop mechanism is released, through the action of the re-

55 tractile spring K.

It is clear that due to the rearward movement of the presser blades or arms during the vertical movement of their shafts, the nailed and strapped boxes may be more readily removed from the press and attention is further called to the equalizing bar G which transmits equal movement to the presser shafts H under normal condition, and which provides for a greater movement

60 of one of the shafts when necessary through

the swiveled connections which the bar has with both the foot lever and the presser shafts themselves.

Attention is further called to the fact that through the simple frictional stop mechanism, before described, the operator is in a position to effectually control the several movements at all times.

I claim:

1. In a press of the character described, 75 the combination of a substantially rectangular frame, a table supported upon the upper forward portion of the frame, said frame including rear uprights extended above the table and at the rear thereof, upright tubular supporting members rigidly connected to the said extended frame uprights and provided intermediate their ends with vertical guide slots, the upper ends of which are curved inwardly, shafts mounted 80 through the tubular uprights and having intermediate pins extending into the guide slots thereof, angular arms carried by the upper ends of the said shafts, presser blades adjustably carried by the said arms, a beam 85 connecting the upper ends of the extended frame uprights, an equalizing bar extending horizontally within the frame and having swiveled connections at opposite ends with the lower ends of the said shafts, a foot lever 90 having a foot piece at its forward end and having a hinged connection within the lower portion of the frame at its rear end, a brake bar movable in the frame, members carried by the foot lever and movable to frictionally 95 engage the said bar and lock the lever in position, a swiveled connection between the foot lever and the equalizing bar intermediate their ends, and a retractile spring connected at its lower end to a point intermediate the equalizing bar and having connection at its upper end with the beam connecting upper ends of the extended frame 100 uprights.

2. In a press of the character described, 110 the combination of a supporting frame, vertically movable partially rotatable shafts journaled in upright positions at the rear side portions of the frame, a foot lever hinged within the frame, a horizontal 115 equalizing bar extending within the frame and having an intermediate swiveled connection with the said foot lever and having swiveled connections at its ends with the lower portions of the said shafts, and presser blades carried by the upper ends of the shafts, all for the purpose described.

3. In a press of the character described, 120 the combination of a supporting frame, tubular guide members secured in upright 125 positions at the rear side portions of the frame, vertically movable and partially rotatable shafts journaled through the tubular guide members, presser blades carried by the upper ends of the said shaft, and a foot 130

lever fulcrumed in the frame and having connecting means with which the lower ends of the said shafts are swivelly engaged.

4. In a press of the character described, 5 the combination of a foot lever having a brake bar, friction engaging members carried by the foot lever and adapted to engage the relatively opposite sides of the brake bar at non-alined points, and a pivoted trip 10 mounted on the foot lever and carrying one of said friction engaging members, for the purpose described.

5. In a press of the character described, the combination of a supporting frame,

posts mounted in upright positions within 15 the frame, and vertically movable with respect thereto, the upper portions of the said posts extending above the frame and being provided with laterally projecting presser blades at their upper ends, connections for 20 moving the posts vertically, and means whereby to cause rotative movement of the posts during their vertical movement, all for the purpose described.

AUGUSTUS RENTZ STEVENS.
